UNITED STATES PATENT OFFICE.

JESSE M. CURTICE, OF KANSAS CITY, MISSOURI.

DESIGN FOR A KITCHEN-CABINET.

SPECIFICATION forming part of Design No. 24,945, dated December 3, 1895.

Application filed October 18, 1895. Serial No. 566,153. Term of patent 14 years.

To all whom it may concern:

Be it known that I, JESSE M. CURTICE, a citizen of the United States, residing at Kansas City, in the county of Jackson and State of Missouri, have invented and produced a new and original Design for Kitchen-Cabinets, of which the following is a specification, reference being had to the accompanying drawing, showing a part thereof.

My invention relates to a new and original design for kitchen-cabinets; and the leading feature of my design consists in a cabinet a portion of the front of which is flat and vertical and a portion beveled or inclined outwardly and a vertical series of circular projections in the center of the vertical flat front.

A represents the upper or body portion of the cabinet, having a vertical flat front face, and B indicates the outwardly-inclined or beveled base portion.

C represents a vertical series of circular projections in the center of the vertical flat front.
